UNITED STATES PATENT OFFICE

2,237,367

SWITCHBOARD

William M. Scott, Jr., Bryn Mawr, Pa., assignor to
 I-T-E Circuit Breaker Company, Philadelphia,
 Pa., a corporation of New Jersey

Original application August 27, 1938, Serial No.
 227,089. Divided and this application January
 18, 1939, Serial No. 251,500

10 Claims. (Cl. 175—298)

My invention relates to switchboards, particularly switchboards of the type comprising circuit-controlling apparatus such as switches, circuit breakers, and the like, removable as units from the switchboard.

In accordance with my invention, a removable circuit-breaker unit includes racking gear which is interlocked with tripping means of the circuit breaker to prevent withdrawal of the circuit-breaker unit from "service" position until the 10 circuit breaker is tripped, to determine a "test" position, to prevent closure of the circuit-breaker when the unit is intermediate its "service" and "test" positions, and to ensure tripping of the circuit breaker during movement of the unit 15 from "test" to "service" position.

This application is a division of my copending application Serial No. 227,089, filed August 27, 1938.

In accordance with another aspect of my invention, the withdrawal circuit-breaker unit also includes racking gear which is interlocked with means for manually tripping of the circuit breaker to prevent withdrawal of the unit from "service" position until the circuit breaker is tripped, to determine a "test" position, to prevent closure of the circuit breaker when the unit is intermediate its service and test positions, and to insure tripping of the circuit breaker during movement of the unit from "test" to "service" position.

My invention further resides in the features of construction, combination and arrangement hereinafter described and claimed.

For an understanding of my invention, reference is to be had to the accompanying drawings in which:

Fig. 1 is a front perspective view of a switchboard with a plurality of truck type circuit breakers in service position;

Fig. 2 is a perspective view of the rear of the switchboard of Fig. 1 with some of its panels removed;

Fig. 3 is a perspective of part of the switchboard of Fig. 1 with the truck units completely withdrawn and not shown;

Fig. 4 is a side view in section of one of the truck units of Fig. 1 and of its associated switchboard unit;

Fig. 5 is a perspective view on enlarged scale and with parts broken away of a disconnect arrangement shown in Fig. 4;

Figs. 6 and 7 are plan views in section illustrative of the relative positions of the truck and

switchboard units when their disconnect contacts are engaged—Fig. 6, and disengaged—Fig. 7;

Figs 8 and 9 are rear and front perspective views of the truck unit of Fig. 4;

Fig. 10, in perspective, illustrates the essential elements of the circuit-breaker operating mechanism and the truck racking gear;

Figs. 11a—11d illustrate different positions of elements of Fig. 10 referred to in explanation of the interlocking relations between the racking gear and the tripping mechanism of the circuit breaker.

Referring to Fig. 1, the switchboard SB is a rectangular metal-clad structure containing bus bars, cable connections, and one or more truck or withdrawal type circuit breakers B1—B6. The stationary structure S, Figs. 2 and 3, of the switchboard comprises units S1—S6, corresponding in number with the circuit breakers, suitably mounted in alignment with each other.

The ends E, E of the switchboard are suitably reinforced steel panels attached to the end units S1, S6 and are substantially wider than the side panels of the units. Each of the units S1—S6 consists of three compartments vertically aligned, individually covered with removable steel panels, and separated or sealed by horizontal steel barriers. Since all units are, or may be similar in construction, only one of them need be described. Referring to Fig. 4, the uppermost compartments 1 and 1a, of a unit S, exemplary of any of units S1—S6, are sealed from the next lower compartment 2 by the horizontal steel barrier 3; the upper wall 4 of the compartments 1, 1a is a steel plate forming the top of the unit; the rear wall of the compartment 1 is the removable steel cover plate 5; and the sides of the compartment 1 are formed by side plates 6 extending from top to bottom of the unit. The steel partition 7 isolates the two compartments 1 and 1a from each other.

The upper compartments 1, 1a contain auxiliary apparatus such as potential transformers PT, relays, and wiring from control and signal contacts 8 which are suitably mounted on the under side of that portion of the bottom of compartment or duct 1a which projects beyond the front wall of compartment 2. Other auxiliary apparatus as meters M, control switches and the like, may be mounted upon the rear face (Fig. 4) of panel 5 for observation or operation from the rear of the switchboard.

Within the compartment 2 are supported the three bus conductors 9, 9a, 9b each wrapped in phenolic insulation, molded and cured in posi-

tion and clamped in the impregnated maple blocks 10, 10a (Fig. 2) to withstand short-circuit stresses. To each tubular bus is directly attached a support 11 for disconnect contacts 12 whose purpose and construction are hereinafter described. Each of the disconnect contact assemblies for a bus conductor is enclosed in its individual housing 13 of insulating material. The rear wall of compartment 2 comprises the removable metal panel 14 and the front wall thereof comprises the upper part of the panel 15, of insulating material and in which there are three staggered slots 16 for permitting contacts 17 extending from the rear of the circuit-breaker unit B to pass through the panel into the similarly staggered disconnect housings 13. Thus, when the unit B is withdrawn, it is impossible for an attendant accidentally to touch any uninsulated parts at high potential.

The bottom compartment 18 of the unit S, 20 whose rear face is closed by the removable steel panel 19, contains cable disconnect contacts, suitably encased in insulating housings 20, current transformers CT, and the outgoing cable connections therefrom. The housings 20 are supported, as by insulators 21 from the cross brace 22, in alignment to receive the contacts 23 which pass through slots 24 in the lower part of panel 15 from the rear of the breaker unit B. The duct 25 along the front face of compartment 18 may 30 be used to encase the wires from the transformers CT to a protective relay or electromagnet hereinafter identified. Access to the interior of duct 25 may be had by removal of the steel panel 25a.

Extending from the front of each unit 35 (S1—S6) are the rails 26 for guiding the wheels 27 of its associated circuit breaker unit (B1—B6), a pair of lugs 28 whose purpose will hereinafter be described, and a dust shield member 29 for the auxiliary contacts 8. The rails 26 extend upwardly from the steel base 30 from which also extends the tripping cam 31 whose purpose will hereinafter appear.

The steel base 30, comprising plates and structural members, extends the length of the switchboard and forms a foundation to which the units are secured.

Reverting to the arrangement providing for disengageable connection of the bus conductors with disconnect contacts 17 of the circuit-breaker unit B, the support 11 for the bus disconnect contacts 12 comprises two members 11a, 11b (Fig. 5) of metal which are clamped by bolts 32 directly to the bus conductor 9. From the front of member 11b extend the brackets 33 for supporting the pins 34, 35 upon which the upper and lower contacts 12 are respectively pivotally mounted. The upper and lower contacts 12 of each of the several groups shown in Fig. 5 are biased toward each other by a spring 36 which encircles a bar 37 through which loosely extend two yoke members.

The upper equalizing yoke 38 presses downwardly on the upper face of two adjacent upper contacts 12; a similar yoke (not shown) bears against the under faces of the corresponding pair of lower contacts 12. The pin 39 passes loosely through forward ends of all of the upper contacts 12 and similarly pin 40 passes loosely through the forward ends of all of the lower contacts 12. This contact construction, more fully described in United States Letters Patent #2,029,028 to Kneass et al., insures equal distribution of the contact pressure between contacts 12 and 17 notwithstanding their appreciable misalignment.

The housing 13 which is assembled about the bus disconnect structure after the latter has been clamped to the bus conductor comprises two separable parts held together as by screws 41. Across 5 the open front end of the housing extend two pivotally mounted shutters 42 of insulating material biased toward engagement with each other by springs 43. The gap between the forward edges of the shutters is in alignment with the corresponding slot 16, Fig. 4, in the panel 15. When the circuit-breaker unit B is pushed into position, each of the disconnect contacts 17 enters its corresponding slot 16, separates a pair of shutters 42, and slides between the upper and lower disconnect contacts 12. When the unit B is completely withdrawn, the shutters 42, 42 within each housing 13 close the corresponding panel slot 16 and preclude accidental contact with the disconnect contacts 12.

As more apparent from Fig. 2, the bus conductors and live parts connected thereto are completely insulated and effectively isolated from each other. The bus conductors, as previously stated, are encased in insulation except within the insulating housings 13, and each disconnect contact assembly is within its individual housing 13 of insulation. When panel 14 is opened, there is, therefore, no possibility of accidental contact with any of the live parts within compartment 2. Moreover, as shown in Figs. 6 and 7, the sides 6, 6 of the unit S so far overlap the sides of the circuit-breaker unit B that it is not possible for an attendant to touch the contacts 17 until after the unit B has been so far withdrawn from the switchboard that contacts 17 are out of engagement with the live disconnect contacts 12.

Each of the truck units B1—B6, exemplified by unit B, Figs. 4, 8 and 9, is a substantially rectangular structure formed by angle iron and sheet steel suitably joined as by welding. The door 44 which permits access to the circuit-breaker mechanism hereinafter described is provided near the top with a louvered opening 45 to permit escape of gases incident to circuit interruption and alternate circulation of air for cooling. In the particular construction shown in Figs. 4, 8 and 9, the top of the truck structure is closed by a sheet metal wall 46.

The circuit breaker and its operating mechanism is removable as a unit from the rear of the truck structure. The framework 51 of the unit comprises a sheet-steel and angle iron structure having a vertical wall 47 and a horizontal wall 48 connected and braced by gusset plates 49 having therein holes 50 to receive crane hooks. Holes 50 are approximately in line with the center of the center of the gravity of the unit to facilitate its manipulation while suspended from a crane.

When the unit is in position, its wall 47 serves as the lower part of the rear wall of the upper or circuit-breaker compartment of the truck; the upper part of the rear wall of the truck compartment is an integral part of the truck structure.

The frame 51 is slidable along and supported by the angle irons 52 extending across the sides of the truck and is held in position by bolts 53 (Fig. 4) which pass through the angle pieces 54 projecting rearwardly from the rear wall 47 of the frame 51. The brackets 55 serve to guide racking links hereinafter described.

The upper face of the horizontal panel 48 and the front face of the vertical wall 47 are covered or lined with the panels 57, 58 of insulating ma-

terial. The strips 59 of insulating material projecting upwardly from panel 57, and similar strips 60 extending forwardly from panel 58 form slots for receiving the bottom and rear edges of the panels 61 of an interpole barrier unit. The rear wall of the truck is internally faced with a panel 58a of insulation which is, in effect, a continuation of panel 58 and from it project the strips 60a of insulation which are, in effect, continuations of the strips 60. The top of the unit 62 is closed by panel 63 which, like panels 61, is of insulating material. The front of the interpole barrier unit is closed by panel 64 of insulating material from the bottom thereof to a level somewhat below that of louver 45 (Fig. 4) leaving the upper, forward parts of the isolated compartments formed by the panels 61, 64, 57 and 58 open for discharge of arc gases. Preferably, short horizontal ledges 64b project inwardly of the compartments from or adjacent the upper edge of panel 64 to prevent the arc gases from flowing downwardly and adjacent the parts of the circuit breaker, and within each compartment above the ledge 64b is fastened the arc gas deflector plate 64a, also of insulation.

The interpole barrier unit is removable from the front of truck structure B by opening door 44 and pulling the barrier unit forward in the slots provided by guides 59. Handles 64c may be provided to facilitate the withdrawal.

The circuit breaker shown herein is a three-pole breaker but since the construction of all three poles are similar, only one need be described. Referring to Fig. 4, the upper main contact assembly 65 comprises a stud 66 which passes through the sleeves 67, 68 of insulating material. By tightening nut 70 on stud 66, the two sleeves 67, 68 are forced tightly against opposite sides of the vertical wall 47 of frame 51. Similarly, the lower main contact assembly 71 is mounted upon a stud 72 which passes through sleeves 73, 74 of insulating material. By tightening nut 76, the sleeves 73, 74 are clamped to opposite sides of the rear vertical wall of the frame 51.

The disconnect contacts 17, 23 are held to the studs 66, 72 by the nuts 77, 78, respectively. The upper end of each of the disconnect contacts 17 is braced by an insulator 79, Fig. 8, to resist bending during insertion and withdrawal of the circuit-breaker unit B from the switchboard. The insulators 79 are secured to and project horizontally from the rear face of the upper part of the steel wall 47 of frame 51.

Preferably, the portion of wall 47 which supports insulators 79 lies in a plane farther to the rear than the plane of that portion of the wall from which the studs 66, 72 extend. The uppermost portion of wall 47 is provided with a series of holes through which pass screws 81, Fig. 4, for securing it to the rear face of the truck. These screws, as well as screws 53, are removed for withdrawal of the frame 51 on which all of the contact structure and operating mechanism therefor is mounted.

The main contact assemblies 65 and 71 are mechanically interconnected by the insulator 84 which resists forces, due to flow of heavy currents, tending to move the assemblies away from each other. The insulator 85 mechanically connected to the frame member 86 of assembly 71 and to the base plate 48 of the unit frame 51 stiffens or supports the assembly 71 against forces or shocks incident to the opening and closing movements of the parts of the circuit breaker.

The upper main contact assembly, Fig. 4, comprises the main contact member 87, the auxiliary contact member 88, the arcing horn 89, the arcing tip 90, and blowout coil 91.

The lower main contact assembly 71, Fig. 4, comprises the stationary frame member 86 within which is pivotally mounted the movable frame member 103 connected by pigtail to the stationary frame member and to the bridging contact member 105 loosely pivotally mounted in the movable frame member 103.

To the upper end of movable frame member 103 is attached the arcing contact 115 which, when the circuit breaker is closed, engages both 15 the auxiliary or shunt contact 88 and the movable arcing horn tip 90. Preferably contacts 115, 88 and 90 are of "Elkonite" or similar arc-resistant material. When the circuit breaker is tripped the contact 115, in moving to its fully 20 open position, separates from the auxiliary contact 88 thus to include the blowout coil 91 in circuit. Shortly after separation of contact 115 from the horn tip 90, the arc extends from the horn 89 to arcing tip 116 of the movable arc contact 115 until the tip 116 moves sufficiently 25 close to the tip 117 of a second, stationary arcing horn 118 connected to the frame 86 and at the same potential as tip 116. When the arc transfers from the tip 117 to the upper arcing 30 horn 119, a second blowout coil 120 is included in circuit further to force the arc upwardly in the arc chute hereinafter described and further to separate the terminals of the arc.

The side panels 138 and end panels 143 of the arc chute are of suitable insulating material; for example, the sides 138 may be of sheet asbestos and the ends 143 of fibre or the like. Within the arc chute above the arcing horns are four groups of spaced plates 144 of insulating material, for example fibre, which serve to split the arc lengthwise as it rises in the chute and as a source of arc-quenching or deionizing gases. The plates of each group are suitably separated as by spacers and held in position by bolts 140a. If the arc rises above plates 144, it is lengthened 45 and split into a large number of arcs in series by the series of copper plates 147 spaced and insulated from each other in the top of the arc chute. These plates serve to quench, muffle, and chill the gases of the arc. Their construction and arrangement is similar to that disclosed and claimed in United States Letters Patent #2,030,582 to Graves.

To facilitate withdrawal of the arc chutes from the truck, each of them is provided with a pair of plates 148 held to the sides 139 of the chute and having holes 149 in their upper ends to receive the ends of an inverted U-shaped link 150 suspended from and slideable along guide bars 151 suitably attached to the under face of the top wall 46 of the truck structure. When the interpole barrier assembly is in place, the links 150 rest upon the top wall 63 of the barrier assembly (Fig. 4), but when the barrier assembly is removed, the links 150 swing downwardly each above its associated arc chute 136 so that the lower ends thereof may be hooked into the holes 149 of the plates 148 of the arc chute.

To assist in alignment of the arc chutes 136, the rear upper end of each of them is received by a notch in the plates 153 of insulation (Fig. 4) which project forwardly from the front face of the vertical wall 47 of the supporting frame for the contact structure of the circuit breaker.

All of the operating mechanism for the circuit

breaker is supported from the under face of the horizontal wall 48 of the frame 51 and the only connections between the movable contact structures and their operating mechanism are the rods 154 which are of insulation; the upper end of each rod 154 is received by a coupling member 155 pivotally connected to the movable frame 103 for the movable contact structure of one pole of the circuit breaker and the lower end of each rod 154 is received by a coupling member 156 pivotally connected to an operating arm 157 (Figs. 4 and 10). All of the operating arms 157 are secured to shaft 158 supported intermediate its ends by a pair of split bearings, one on each of the side plates 162.

The coil 160 which may be energized to effect closure of the circuit breaker is within a housing 161 (Fig. 4) having two sides formed by steel plates 162 which are attached to and depend from the wall 48 of frame 51 and two sides formed by steel plates 163 which extend between, and secured, as by welding, to plates 162. Plates 162, in addition to serving as sides of the coil housing and as bearing plates for shafts of the operating mechanism, also provide feet upon which the circuit-breaker unit may rest when withdrawn from the truck.

The rear wall of the coil housing is formed by the steel plate 164 held in place by screws 165 which pass through plate 164 threadably to engage blocks 166 welded to the inner rear corners of the housing. The front wall of the coil housing comprises steel plate 167 welded in place and provided with an opening to receive the guide tube 168 of non-magnetic metal for the movable core or armature 169. The rear end of the guide tube which supports the coil 160 is received by a circular recess 170 in the rear wall 164 of the coil housing. The stop 171 for limiting the forward movement of the core 169 comprises a plate welded at its opposite ends to the plates 162 beyond the front wall of the coil housing. The core 169 is biased by spring 168a (Fig. 10) to its forward position.

The link 172 pivoted at its rear end to the front end of core 169 is provided with an elongated slot 173 which slidably receives the pivot pin 174 of the toggle links 175, 176. The upper end of toggle link 176 is pivotally connected by pin 177 to that one of the arms 157 which is attached to the central portion of shaft 158 between the plates 162 which support most of the circuit-breaker operating mechanism. The lower end of toggle link 175 is pivotally connected by pin 178 to a bell-crank lever 179 whose pivot pin 180 provides a fixed axis for angular movement of lever 179. The ends of pin 180 are supported by plates 162.

The arm 181 of lever 179 is engageable near its free end by the latching member 182 secured to shaft 183 and biased to its latching position by spring 184. When coil 185 of the tripping magnet 186 is sufficiently energized, as upon occurrence of an overload, the movement of its armature 187 through arm 188 rocks shaft 183 in counterclockwise direction to release the latch 182, whereupon powerful springs 189 (one of which is shown) rocks the shaft 158 to open the circuit breaker.

All of the stresses incident to opening and closure of the circuit breaker are confined to the frame 51 and are not transmitted from one operating part to another through the truck frame. Moreover, since the operating mechanism in its entirety is part of the circuit-breaker unit, it may

readily be assembled and tested as a completely operative unit prior to mounting in the truck. Preferably the kinetic energy of the moving operating parts is absorbed by a friction brake B similar to that disclosed and claimed in United States Letters Patent No. 2,137,001.

The circuit breaker may be tripped manually by depressing the forward or handle end of lever 190 which is pivotally mounted within a housing or bracket 191 secured to the front end of the frame 51. The handle of lever 190, as shown in Figs. 1, 4 and 9, projects through a slot 190a in the door 44 of the truck. When the handle is depressed the extension 192 of lever 190 engages the extension 193 of latch 182 to effect its release from arm 181 and so permit springs 189 to open the circuit breaker.

The circuit breaker may be reclosed manually by inserting a bar 194 through an opening 195 (Figs. 1 and 9) in the truck door and into the slot 196 of a disk 197 loosely mounted, between the sides of bracket 191, on the shaft 198 (Fig. 10). A link 199 connects the disk 197 to the toggle pin 174. After the bar 194 is so inserted, it is swung downwardly through an arc of about 90° and so moves pin 174 to the left thus to rock the shaft 158 in clockwise direction to lift the rods 154 and so effect circuit-closing movement of the movable contacts of the circuit breaker. If an overload exists, the circuit-breaker cannot be held closed by bar 194 because when the latch 182 is released, the toggle collapses and springs 189 are free to open the circuit breaker regardless of the position of disk 197. The construction and operation of the operating mechanism is similar to that disclosed and claimed in Reissue Patent No. 19,753 to H. C. Graves.

Preferably, the edge of disk 197, which is visible through opening 195 in the truck door 44 is colored or otherwise marked to indicate whether the circuit breaker is in open or closed circuit position. The disk 197 is biased by spring 200 to the "open circuit" position so that it will move to that position when bar 194 is removed or released after tripping of the breaker during manual closure thereof. Spring 200 also restores the arm 181 to its latching position after tripping of the circuit breaker in readiness for the subsequent resetting of the toggle incident to automatic or manual reclosure of the circuit breaker.

From the tripping lever 190 is suspended the rod 201 which extends through the base of the truck in line with the cam 31 on the base 30 of the switchboard to trip the circuit breaker, if it be closed, as the truck is pushed into the switchboard.

The bar 202 pivotally suspended from arm 157a on the operating shaft 158 of the circuit breaker is utilized to operate the auxiliary switches 203 mounted upon the panel 204 suitably mounted in the lower compartment of the truck. These switches may be used to operate signal lights or perform other control functions in accordance with the position of the circuit breaker.

Each truck unit B1—B6 is locked in its innermost or normal position by a pair of racking bars 205 (Fig. 4) each having a hooked end which drops over and engages the pin 206 of one of the pair of abutment members 28 attached to the front face of each of the switchboard units S1—S6; the rear face of the hooked end is suitably sloped so that if it is down when the truck is pushed into the switchboard the engagement of the sloping end with pin 206 causes the bar to lift and drop over the pin. The other end of each

bar 205 is pivotally connected to a crank arm 207 secured to shaft 198 to which is secured the notched disk 208 accessible through the opening 185 in the door 44 of the truck. The ends of this shaft are supported in bearings in brackets integral with the circuit-breaker frame.

To release bars 205 from pins 206 and move the truck B to such extent from the switchboard unit S that all circuit connections between them are broken, the shaft 198 is rotated a half revolution from the position shown in Figs. 10 and 11a. To effect this movement, a bar or rod 194a is inserted by the operator in the notch 208a of disk 208 substantially in alignment with the stop 191a defined by the lower edge of housing 191 and then 15 swung upwardly, through an arc of about 90°, until arrested by stop 191b defined by the upper edge of housing 191; the bar 194a is then removed and reinserted in notch 208b of disk 208 and again moved upwardly through an arc of somewhat less than 90°. Throughout substantially all of the resultant movement of cranks 207 effected by the two-step racking movement of bar 194a, the rear ends of the bars 205 remain in engagement with and press against the abutments 28 so that the 20 25 counterclockwise rotation of the cranks 207 from the position shown in Figs. 11a to the 180° displaced position shown in Fig. 11d effects a forward movement of the truck B. Somewhat before completion of the 180° movement of cranks 207, 30 the bars 205 rest intermediate their ends upon the abutments 209 so that further movement of the cranks in the same (counterclockwise) direction causes the bars 205 to pivot about the abutments 209 and so lift their hooked ends free of 35 the pins 206.

When the circuit-breaker unit B is in its normal or service position shown in Fig. 4, the disk 208 is in the position shown in Fig. 11a with its notch 208c receiving the upper end of the vertically, 40 slideable pin 210 which is pivotally mounted upon the manual tripping lever 190 biased to non-tripping position by spring 211. The notch 208c and notch 208d for the pin 210 are out of the plane of the notches 208a, 208b so that, except when the pin 210 is received by one or the other of notches 208c or 208d, it is impossible to close the circuit breaker. Before the circuit-breaker truck can be moved from the position shown in Fig. 4, and before disk 208 can be moved from the position shown in Fig. 11a to the 90° displaced position shown in Fig. 11b, the handle 190 must be depressed thus to insure the circuit breaker is open before the disconnect contacts 17 of the truck B separate from the disconnect contacts 12 of the 45 switchboard.

To provide a "test" position in which the circuit breaker, while its main contacts are out of circuit with the bus conductors, can be operated by control circuits through the contacts 8, the disk 208 is provided with a flattened cam notch 208d into which the pin 210 of the trip lever 190 rides (Fig. 11c) as the disk 208 approaches the end of its aforesaid second 90° movement. Engagement of the pin 210 with the shoulder 212 can be felt by the operator who is thus informed the truck has reached the "test" position. In this position the circuit breaker can be opened and closed either automatically or manually, and operation of its parts observed without danger to the operator and without need completely to withdraw the truck from the switchboard.

With the circuit breaker truck in "test" position and the circuit breaker closed, the breaker must be tripped manually before the lever 194a 70 75

can further be raised to complete the second 90° movement of the disk 208 (from the position shown in Fig. 11b to the position of Fig. 11d).

The disclosed construction of disk 208 and its relation to pin 210 also prevents the circuit breaker from being closed when the truck is moved from "test" position toward the switchboard to restore the circuit breaker to its service position and thus precludes completion of the bus to cable circuit when the disconnect contacts 17 and 23 of the truck engage the disconnect contacts of the switchboard. More particularly, when disk 208 is rotated in clockwise direction from Fig. 11c, "test" position, to Fig. 11a, "service" position, the cam face of slot 208d moves pin 210 downwardly and so effects tripping movement of lever 190.

To summarize, the interlock between the racking and tripping mechanisms prevents closure of the circuit breaker for truck positions intermediate the "service" and "test" positions, determines the "test" position during withdrawal of the truck from the switchboard, prevents accidental withdrawal of the truck from "test" position, and effects tripping of the circuit breaker, if closed, as the truck is moved from "test" toward "service" positions.

Features herein described but not claimed are claimed in aforesaid application Serial No. 227,089 and in divisional applications Serial Nos. 331,507 and 331,697, filed, respectively, April 25, 1940 and April 26, 1940.

What I claim is:

1. A circuit-controlling arrangement comprising a fixed unit, a movable unit adapted to be withdrawn therefrom, complementary disconnect contacts mounted on said units, a switch mounted on said movable unit and connected to the disconnect contacts thereof, operating means for closing said switch and releasably retaining it in closed circuit position, tripping means for releasing said switch and for disabling said operating means, manually operable racking means for moving said movable unit from service position in which the disconnect contacts of said units are in engagement to a position in which said disconnect contacts are disengaged, and means for locking said racking means including a member movable to unlock said racking means whether said switch be in open or closed circuit position and concurrently to actuate said tripping means to effect disablement of said switch operating means.

2. A circuit-controlling arrangement comprising a fixed unit, a movable unit adapted to be withdrawn therefrom, complementary disconnect contacts mounted on said units, a switch mounted on said movable unit and connected to the disconnect contacts thereof, operating means for closing said switch and releasably retaining it in closed circuit position, tripping means for releasing said switch and for effectively decoupling it from its said operating means, manually operable racking means for moving said movable unit from service position in which the disconnect contacts of said units are in engagement to a test position in which said disconnect contacts are disengaged, and means for locking said racking means including a member which, with respect to both test and service positions of said movable unit, is movable to lock and unlock said racking means for open and closed circuit positions of said switch, which actuates said tripping means when moved to unlock said racking means, and which for all positions of said movable unit between its service and test positions coacts with said tripping means to

maintain said operating means decoupled from the switch.

3. A circuit-controlling arrangement comprising a fixed unit, a movable unit adapted to be withdrawn therefrom, complementary disconnect contacts mounted on said units, a switch mounted on said movable unit and connected to the disconnect contacts thereof, operating means for closing said switch and releasably retaining it in closed circuit position, tripping means for releasing said switch and for effectively decoupling it from said operating means, manually operable racking means for moving said movable unit from service position in which the disconnect contacts of said units are in engagement to a test position in which said disconnect contacts are disengaged, and means for locking said racking means comprising two interlocking members both carried by said movable unit, one of which is movable in unison with said racking means, and the other of which, with respect to both the test and service positions of said movable unit, may be moved into or out of interlocking relation to said one of said members to restrain or permit operation of said racking means, and which when out of interlocking relation coacts with said tripping means for all positions of said movable unit to maintain said operating means effectively decoupled from the switch.

4. A circuit-controlling arrangement comprising a fixed unit, a movable unit adapted to be withdrawn therefrom, complementary disconnect contacts mounted on said units, a switch mounted on said movable unit and connected to the disconnect contacts thereof, operating means for closing said switch including a toggle for releasably retaining it in closed circuit position, tripping means operable to break the toggle to release said switch and to prevent reclosure thereof by actuation of said operating means, manually operable racking means for moving said movable unit from service position in which the disconnect contacts of said units are in engagement to a second position in which said disconnect contacts are disengaged, and interlocking means between said tripping means and said racking means including a member operable to actuate said tripping means and concurrently to release said racking means for actuation to move said movable unit from either of said positions to the other, and which for all positions of said unit intermediate its second and service positions coacts with said tripping means to prevent resetting of said toggle.

5. A circuit-controlling arrangement comprising a fixed unit, a movable unit adapted to be withdrawn therefrom, complementary disconnect contacts mounted on said units, a switch mounted on said movable unit and connected to the disconnect contacts thereof, operating means for closing said switch and releasably retaining it in closed circuit position, tripping means for releasing said switch and for disabling said operating means, manually operable racking means for moving said movable unit from service position in which the disconnect contacts of said units are in engagement to a position in which said disconnect contacts are disengaged, and interlocking means between said tripping means and said racking means to prevent movement of said movable unit from service position while said switch is closed, to prevent closure of said switch during movement in either direction of said movable unit between service and test positions, to determine the test position, to prevent accidental movement of said unit beyond test position, and

5 to effect operation of said tripping means by initial movement of said movable unit from test toward service position comprising two interlocking members carried by said movable unit, one of which is operable to actuate said tripping means for all positions of said movable unit, and the other of which is moved with respect to said one of said members by said racking means.

6. A circuit-controlling arrangement comprising a fixed unit having power circuit disconnect contacts and auxiliary circuit contacts, a truck on which is mounted circuit-breaker disconnect contacts for engaging said power circuit contacts and other contacts for engaging said auxiliary circuit contacts, racking gear for moving said truck from service position in which all of said contacts are in engagement to a test position in which only said disconnect contacts are out of engagement and from test position to a withdrawn position for which all of said contacts are disengaged, and manually operable means for tripping said circuit breaker, said racking gear including a rotatable member having notches cooperative with an element of said tripping means to prevent movement of the truck to or from service position while said circuit breaker is closed, to permit opening and closure of the circuit breaker when in test position, and to prevent closure of the circuit breaker for positions of the truck between test and service positions.

7. Racking gear for a circuit breaker comprising a shaft supported from the circuit breaker frame, an operating bar, a disk secured to said shaft and having notches therein to receive said operating bar, a crank arm secured to said shaft, a stationary pin, a racking link having a hooked end to embrace said pin and connected at its other end to said crank, and an abutment fixed with respect to said frame and engaged by said link during movement of said frame by said bar to effect release of the hooked end of said link from said pin.

8. A circuit-controlling arrangement comprising a fixed unit including power circuit disconnect contacts, and a circuit breaker unit withdrawable from said fixed unit comprising disconnect contacts and a circuit breaker having contact structure electrically connected thereto, a stationary pin on said fixed unit, racking gear for effecting withdrawal of said circuit-breaker unit comprising a link having a hooked end for embracing said pin, means for operating said link including an actuating bar, a disk having a notch for receiving said actuating bar and a shaft to which said disk is secured, means for tripping the circuit breaker including an interlocking member received by a notch in said disk, and means for closing the circuit breaker including a disk loosely mounted on said shaft and notched to receive an operating bar.

9. A circuit-controlling system comprising a fixed unit, a movable circuit breaker unit adapted to be withdrawn therefrom, complementary disconnect contacts mounted on said units, racking means operable to move said movable unit toward and from service position in which said contacts are in engagement, a member movable to one position to lock said racking means and to a second position to unlock said racking means and trip the circuit breaker, means for closing said circuit breaker including a disengageable mechanical connection broken so long as said member is in its said second position, and structure preventing movement of said member to its lock-

ing position for positions of said movable unit other than said service position.

10. A circuit-controlling system comprising a fixed unit, a movable circuit breaker unit adapted to be withdrawn therefrom, complementary disconnect contacts mounted on said units, racking means operable to move said movable unit from service position in which said contacts are in engagement to a test position in which said contacts are out of engagement, a member movable to one position to lock said racking means and to a second position to unlock said racking means

5 and trip the circuit breaker, means for closing said circuit breaker including a disengageable mechanical connection broken so long as said member is in its said second position, and structure permitting movement of said member to its locking position, for both the service position and the test position of said movable unit, and maintaining said member in its said second position for positions of said movable unit other than its said service and test positions.
